[57] CLAIM

The ornamental design for a pulse detector stopwatch, as shown and described.

DESCRIPTION

FIG. 1 is a perspective view of the pulse detector stopwatch of the invention with the door thereof open;

FIG. 2 is a front view of the pulse detector stopwatch of the invention with the door thereof open;

FIG. 3 is a view taken from the right side of FIG. 2;

FIG. 4 is a rear view of the pulse detector stopwatch;

FIG. 5 is a view taken from the left side of FIG. 2;

FIG. 6 is a top view of the pulse detector stopwatch as seen in FIG. 2;

FIG. 7 is a bottom view of the pulse detector stopwatch as seen in FIG. 2;

FIG. 8 is a perspective view of the pulse detector stopwatch with the door thereof closed; and,

FIG. 9 is a front view of the pulse detector stopwatch with the door thereof closed.
